CONTAINER END

Christian Frederick Kinkel, Arlington Heights, and Burton Frank Pillnik, Cary, Ill., assignors to American Can Company, Greenwich, Conn.

Filed May 7, 1971, Ser. No. 141,456

Term of patent 14 years

Int. Cl. D9—07
U.S. Cl. D9—255

FIG. 1

FIG. 2

FIG. 3

FIG. 1 is a top plan view of a container end showing our new design;

FIG. 2 is a bottom plan view thereof; and

FIG. 3 is an enlarged sectional view thereof taken along line 3—3 of FIG. 1.

We claim:

The ornamental design for a container end, substantially as shown.
